UNITED STATES PATENT OFFICE.

DEWANE B. SMITH, OF DEERFIELD, NEW YORK.

DESIGN FOR A BODY AND BASE FOR BICYCLE-PUMPS.

SPECIFICATION forming part of Design No. 28,899, dated June 21, 1898.

Application filed May 28, 1898. Serial No. 682,071. Term of patent 3½ years.

To all whom it may concern:

Be it known that I, DEWANE B. SMITH, a citizen of the United States, residing at Deerfield, county of Oneida, and State of New York, have invented and produced a new and original Design for the Body of a Bicycle-Pump, of which the following is a specification, reference being had to the accompanying drawings, forming part hereof.

10 Figure 1 is a perspective view of a bicycle-pump body, including a base, showing my design. Fig. 2 is a side elevation of the same.

As shown in the drawings, the leading or material features of my design consist of the

15 cylindrical barrel 1, having an external rib 2, mounted in the side projecting base 3, having a collar-like portion 4, all arranged as shown in the drawings.

Having described my invention, what I claim as new, and desire to secure by Letters Patent, is—

The design for the body and base of a bicycle-pump as herein shown and described.

In witness whereof I have affixed my signature, this 21st day of May, 1898, in the presence of two witnesses.

DEWANE B. SMITH.
